US0D1087510S

(12) **United States Design Patent** (10) Patent No.: **US D1,087,510 S**
(45) Date of Patent: ** Aug. 5, 2025

(54) **ROBOT VACUUM CLEANER**

(71) Applicant: **LG ELECTRONICS INC.**, Seoul
(KR)

(72) Inventors: **Seongmin Kim**, Seoul (KR); **Yunseo Jang**, Seoul (KR)

(73) Assignee: **LG ELECTRONICS INC.**, Seoul
(KR)

(**) Term: **15 Years**

(21) Appl. No.: **35/520,077**

(22) Filed: **Feb. 23, 2023**

(80) **Hague Agreement Data**

Int. Filing Date: **Feb. 23, 2023**

Int. Reg. No.: **DM/227382**

Int. Reg. Date: **Feb. 23, 2023**

Int. Reg. Pub. Date: **Feb. 23, 2024**

(30) **Foreign Application Priority Data**

Oct. 4, 2022 (KR) 30-2022-0040535

(51) **LOC (15) Cl.** **15-05**

(52) **U.S. Cl.**
USPC **D32/21**

(57) **CLAIM**

The ornamental design for a robot vacuum cleaner as shown and described.

DESCRIPTION

1. Robot vacuum cleaner

1.1 : Front perspective view

1.2 : Bottom perspective view

1.3 : Front

1.4 : Back

(Continued)

1.5 : Left**1.6** : Top**1.7** : Bottom

The broken lines shown in the reproductions depict portions of the robot vacuum cleaner that form no part of the claimed design; a right view is omitted because it is a mirror image of the left view.
